(57) **CLAIM**

The ornamental design for a camera lens, as shown and described.

DESCRIPTION

FIG. 1 is a perspective view of a camera lens showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged portion view taken from encircled portion labeled, “FIG. 8,” in FIG. 1.

The dashed-dot lines form the boundary of the enlarged portion view of FIGS. 1 and 8 and form no part of the claimed design. The even dashed broken lines shown in the drawings are included for the purpose of illustrating portions of the camera lens that form no part of the claimed design.
